UNITED STATES PATENT OFFICE.

HENRY F. PARKER, OF BROOKLYN, NEW YORK, ASSIGNOR TO THE COAST PIGEON MANUFACTURING COMPANY, OF CUYAHOGA FALLS, OHIO.

DESIGN FOR A FLYING TARGET.

SPECIFICATION forming part of Design No. 26,914, dated April 13, 1897.

Application filed February 26, 1897. Serial No. 625,219. Term of patent 14 years.

To all whom it may concern:

Be it known that I, HENRY F. PARKER, a citizen of the United States, residing at the city of Brooklyn, in the county of Kings and State of New York, have invented and produced a new and original Design for Flying Targets, of which the following is a specification, reference being had to the accompanying drawings, forming part thereof.

Figure 1 is a face view of a target, showing the design; and Fig. 2, a cross-sectional view taken on the line $x-x$, Fig. 1, these two views being deemed necessary to fully illustrate the design.

The design applies to a saucer-shaped target of brittle composition for trap-shooting.

The leading feature of the design consists in a series of corrugated embossments, each

having smooth rounded surfaces and radiating spirally from the center of the target, which embossments are closely arranged, as shown. The corrugations *d* radiate from the center *D* outwardly and spirally to a smooth annulus *C* at the crown, and the corrugations *b* radiate outwardly and spirally from the annulus *C* to the surface of the rim *A*, where they join said surface in a scalloped outline, effectively characterizing the design.

What I claim is—

The design for a flying target herein shown and described.

HENRY F. PARKER.
